UNITED STATES PATENT OFFICE.

LYMAN R. ROBERTS, OF RUTHERFORD, NEW JERSEY, ASSIGNOR TO UNDERWOOD TYPE-WRITER COMPANY, OF NEW YORK, N. Y., A CORPORATION OF DELAWARE.

AUTOMATIC TYPE-WRITER OPERATOR.

1,163,954.

Specification of Letters Patent. Patented Dec. 14, 1915.

Application filed July 2, 1912. Serial No. 707,211.

To all whom it may concern:

Be it known that I, LYMAN R. ROBERTS, a citizen of the United States, residing in Rutherford, in the county of Bergen and 5 State of New Jersey, have invented certain new and useful Improvements in Automatic Type-Writer Operators, of which the following is a specification.

This invention relates to an automatic operator for a typewriter, and more especially to a new and improved line-space operating mechanism therefor.

This invention is an improvement on the application of Lyman R. Roberts and 15 Charles L. Davis, No. 428,050, filed April 20, 1908.

In the above-mentioned application a pair of perforated master-sheets coöperate with tracker boards to control the action of a number of pneumatic actuators for the several parts of the typewriter. Among the others a pneumatic actuator is provided, which connects the line-space lever of the typewriter to a constantly driven member so that the platen 25 may be spaced for a line and the carriage returned. This invention has to do more particularly with this mechanism.

In carrying out this invention, the constantly driven member is shown in the form 30 of a stationary rotating screw. A half nut is mounted on a carrier so as to be shiftable from a normal position out of engagement with the screw to a position in engagement therewith. The nut and carrier are connected by an arm to the usual line-space lever of the typewriter carriage. The carrier is mounted on a pair of rails so as to run with the carriage. A cam star wheel is swung downwardly by a pneumatic actuator 35 to engage, shift and move past one of the rails so as to shift the carrier and thus bring the nut into engagement with the screw. The star wheel is normally held from backward rotation on its downward stroke by a 40 detent, which detent, however, does not prevent the star wheel from rotating idly while passing the shift rail on its return stroke. Means is also provided for moving the detent to an ineffective position when 45 the pneumatic action of the machine stops, enabling the star wheel to rotate idly back-

ward, even on its down stroke, thereby preventing an accidental extra line-spacing when the machine starts up again.

Other features and advantages will hereinafter appear.

In the accompanying drawings, Figure 1 is a fragmentary view showing in general, the relation of the operator to the typewriter. Fig. 2 is a fragmentary view in elevation showing the detent in engagement with the star wheel. Fig. 3 is a view of the parts shown in Fig. 1, and showing the detent disengaged from the star wheel so that the latter is free to rotate idly without having any shifting action when the pneumatic mechanism of the machine, as a whole, is silent. Fig. 4 is a detail perspective view showing the relation of the detent to the star wheel. Fig. 5 is a detail perspective view showing the related mechanism whereby the line-space lever of the typewriter is actuated either to return the carriage or to line-space the platen. Fig. 6 is a detail view showing the star wheel in its normal inactive position before having been depressed by its actuator. Fig. 7 is a view similar to Fig. 6, showing the star wheel in the act of shifting the carrier and its nut to start a movement of the line-space lever.

Referring more particularly to the separate parts of this invention as embodied in the form shown in the drawings, 1 indicates a typewriter which may be of any suitable character, such as the Underwood, and 85 which is adapted to be automatically operated by an operator 2 to reproduce a form letter any number of times with the proper insertion of separate matter for each letter, such as a different name and address. As 90 described in my above-mentioned application, the operator 2 is controlled by a pair of master-sheets 3 and 4 mounted on rollers 5 and 6 so as to be drawn across the face of perforation tracker boards 7 and 8. The 95 perforations in these tracker boards are connected by pipes to pneumatic actuators so that when one of the perforations in the master-sheet comes in register with the corresponding perforation in the tracker board, 100 the associated pneumatic actuator will be actuated to operate some part of the type-

writer, as for example, by depressing its hammer 9 to depress its key 10 of the typewriter.

One of the functions of the typewriter which the pneumatic actuator controls is the line-spacing of the platen and the return of the carriage of the typewriter. In this instance the platen, indicated at 11, is mounted on a carriage 12 in the usual manner and is provided with a line-space mechanism indicated in general at 13. This line-space mechanism is provided, as is usual in the Underwood type of machine, with a line-space lever 14 extending from the front 15 of the machine.

For the purpose of enabling the line-space lever 14 to be actuated at any time, there is provided a continuously driven member, shown in the form of a stationary rotating screw 15, which receives power from any suitable source, indicated by the gearing 16.

Mounted on a carrier 17 in juxtaposition to the screw shaft 15, there is provided a half nut 18 which, when in engagement with the screw shaft 15, will be traversed horizontally. The motion of this nut and carrier may be transmitted to the line-space lever 14 by an arm 19 which is secured at one end to the carrier 17 and is provided at its other end with a loop 20 to engage an up-standing finger grip 21 of the line-space lever 14.

The nut 18 is normally out of engagement with the screw shaft 15, but is capable of being forced into engagement therewith when it is necessary to return the carriage or line-space the platen, as determined by the perforations in either of the master-sheets 3 or 4. To accomplish this the carrier 17 is provided with a pair of rollers 22 which engage a track rail 23 so that the carrier can move horizontally. The upper end of the carrier 17 is also provided with a pair of rollers 24 which engage another rail 25 which may be termed the shift rail, inasmuch as it is used to shift the carrier 17 to control the connection of the half-nut 18 with the screw shaft 15. The shift rail 25 is mounted on a pair of arms 26 which are rotatably mounted on the track rail 23.

When one of the line-space or carriage return apertures in the master sheet comes in register with its accordant aperture in the tracker board, air is admitted to a pneumatic control 27 so that a pneumatic actuator, shown in the form of a collapsible bellows 28, is operated to draw down on arm 29 against the tension of a spring 30. The arm 29 is adjustably but rigidly connected to a slide 31 which is slidingly and pivotally mounted, as by means of a pin-and-slot connection 32.

Mounted on the slide 31 there is provided a shifter for the shift rail 25, shown in the

form of a cam star wheel 33 rotatably mounted on a stud shaft 34. In the normal position of the slide 31 the shift rail 25 is located, as shown in Fig. 6, in the depression between two teeth of the star wheel. When the slide 31 starts to move down, however, the star wheel 33, which is held from backward rotation by a detent 35, acts as a cam against the shift rail 25 forcing it from the position shown in Fig. 6 to the position shown in Fig. 7, thereby bringing the nut 18 into engagement with the screw shaft 15. As soon as this position is arrived at, a spring-pressed catch 36 is slid in back of one of the arms 26 so that an enlarged portion 37 thereon will prevent the return of 80 the shift rail 25 and the carrier 17 as the point of the star wheel moves downward beyond the shift rail 25 and until this catch 36 has been released. Of course, the engagement of the nut 18 with the screw shaft 85 15 will traverse the carriage and nut to the left as viewed in Fig. 5, carrying with it the line-space lever 14 and the carriage. When the limit of motion has been reached, the carrier 17 will come into engagement with 90 the catch 36 forcing it to the left against the tension of the spring, thereby permitting the carrier and its nut to return to the normal position shown in Fig. 6. When the pneumatic actuator 28 is permitted to return 95 by the apertures in the master-sheet moving away from the apertures in the tracker board, the slide 31 is free to return under the traction of the spring 30 to its normal position.

If the detent 35 would hold the star wheel 33 from rotation in both directions, the shift rail, which, when released from the catch 36 is again seated between two points of the star wheel, would again be actuated, but the 105 detent 35 is bent at its upper end so that it will prevent only the backward rotation and will yield outwardly against the tension of its spring 38 during the upward stroke of the star wheel 33. The teeth of the star 110 wheel are cut away as at 39 on one side so as to enable the detent to be readily forced out during the return motion of the star wheel. It will thus be seen that instead of the star wheel forming a rigid intermediary, 115 it rotates idly on its upward stroke without shifting the rail 25.

In order to avoid accidental double line-spacing where certain parts of the machine are stopped at the instant when the line-space 120 actuator is in operation, means is provided for rendering the shifting mechanism ineffective when the operation of the machine is stopped. In order to understand this feature it may be well to describe how the typewriter operator can be stopped in its action. The rollers 5 and 6 which carry the master-sheets 3 and 4 are provided with gears 40

- and 41 respectively, which are driven by gears 42 and 43 mounted respectively on rockers 44 and 45 which are depressed or raised alternatively by a shifter 46. When it is desired to manually stop the driving of both of the rollers at the same time, a hand knob 47 is rotated so as to rock an arm 48 to depress an arm 49, thereby rocking a shaft 50. The shaft 50 is also provided with a second arm 51 which is connected by a link 52 to a bell crank 53 having a lug underlying the shaft on which the gear 43 is mounted. One of the arms of the bell crank 53 is connected by a link 54 to an arm 55^a having a lug underlying the shaft on which the gear 42 is mounted. It will thus be seen that both of the gears 42 and 43 can be lifted out of mesh at the same time, thereby stopping the action of the machine. Another way in which these gears can be moved out of mesh is by means of a pneumatic actuator indicated in general at 55, which is brought into action when the paper supply runs out. This causes a collapse of the bellows which forms a part of the pneumatic actuator. so that a hook 56 is drawn down, and this hook is pivotally mounted on the arm 49 so that the shaft 50 is once again rocked. All of this mechanism is shown and described more fully in the above-mentioned application and specifically forms no part of this invention. However, when the gears 42 and 43 are lifted out of mesh concomitantly to stop the action of the machine, whether by one means or the other, this action at the same time renders the shifting mechanism for the line-space mechanism ineffective so as to prevent a false carriage return and line-spacing action when the machine is started up again. To accomplish this the shaft 50 is also provided with a third arm 57 upon which is pivotally mounted a thrust link 58. The lower end of this thrust link extends through a guide opening 59 provided in an extension arm 60 of the 45 50 55 60 65 70 75 80 85 90 95 100 105 110 115 120 125
- detent 35. Secured on the thrust link 58 there is provided a collar 61 which when the shaft 50 is rocked to depress the link 58, will come into engagement with the arm 60 so as to lock the detent 35 out of engagement with the teeth of the star wheel 33. When this occurs the star wheel will be free to rotate when it is carried downwardly without shifting the rail 25.
55. Variations may be resorted to within the scope of the invention, and portions of the improvements may be used without others.
- Having thus described my invention, I claim:
60. 1. The combination with a typewriter having a line-space mechanism, of an operator for said typewriter having actuating means for operating said line-space mechanism, and a one-way acting shifting means engaging said first-mentioned means on one stroke to shift the same and ineffectively engaging said first-mentioned means on its return stroke.
2. The combination with a typewriter having a line-space mechanism, of an automatic operator for said typewriter having actuating means for said line-space mechanism, and cam means for controlling the effectiveness of said actuating means.
3. The combination with a typewriter having a line-space mechanism, of an automatic operator for said typewriter having actuating means for said line-space mechanism, cam means for controlling the effectiveness of said actuating means, and means for rendering said cam means ineffective.
4. The combination with a typewriter having a carriage, of an automatic operator for said typewriter having carriage-returning means, and shifting means engaging said carriage-returning means to render the same effective on one stroke and ineffectively engaging said carriage-returning means on its return stroke.
5. The combination with a typewriter, of an automatic operator for said typewriter, said typewriter having a finger grip thereon whereby certain parts of said typewriter may be actuated by said operator, said automatic operator including a continuously driven member, means connected to said finger grip adapted to be operatively connected to said continuously driven member so as to manipulate said finger grip, a shift rail connected to said means, and a star wheel movable to shift said shift rail by engagement therewith.
6. The combination with a typewriter, of an automatic operator for said typewriter, said typewriter having a finger grip thereon whereby certain parts of said typewriter may be actuated by said operator, said automatic operator including a continuously driven member, means connected to said finger grip adapted to be operatively connected to said continuously driven member so as to manipulate said finger grip, a shift rail connected to said means, a star wheel movable to shift said shift rail by engagement therewith, and a detent arranged to permit the rotation of said star wheel in one direction and to prevent the rotation of said star wheel in the opposite direction.
7. The combination with a typewriter, of an automatic operator for said typewriter, said typewriter having a finger grip thereon whereby certain parts of said typewriter may be actuated by said operator, said automatic operator including a continuously driven member, means connected to said finger grip adapted to be operatively connected to said continuously driven member so as to manipulate said finger grip, a shift

rail connected to said means, a star wheel movable to shift said shift rail by engagement therewith, a detent arranged to permit the rotation of said star wheel in one direction and to prevent the rotation of said star wheel in the opposite direction, and silencing means for moving said detent to an ineffective position.

8. The combination with a typewriter, of an automatic operator for said typewriter, said typewriter having a finger grip thereon whereby certain parts of said typewriter may be actuated by said operator, said automatic operator including a continuously driven member, means connected to said finger grip adapted to be operatively connected to said continuously driven member so as to manipulate said finger grip, a shift rail connected to said means, a star wheel movable to shift said shift rail by engagement therewith, a detent arranged to permit the rotation of said star wheel in one direction and to prevent the rotation of said star wheel in the opposite direction, and means for concomitantly silencing said automatic operator and moving said detent to an ineffective position.

9. The combination with a typewriter, of an automatic operator for said typewriter, said typewriter having a finger grip thereon whereby certain parts of said typewriter may be actuated by said operator, said automatic operator including a continuously driven member, means connected to said finger grip adapted to be operatively connected to said continuously driven member so as to manipulate said finger grip, a shift rail connected to said means, a star wheel movable to shift said shift rail by engagement therewith, and an actuator for said star wheel.

10. The combination with a typewriter, of an automatic operator for said typewriter, said typewriter having a finger grip thereon whereby certain parts of said typewriter may be actuated by said operator, said automatic operator including a continuously driven member, means connected to said finger grip adapted to be operatively connected to said continuously driven member so as to manipulate said finger grip, a shift rail connected to said means, a star wheel movable to shift said shift rail by engagement therewith, and master-sheet controlled-actuating means for actuating said star wheel.

11. The combination with a typewriter, of an automatic operator for said typewriter, said typewriter having a finger grip thereon whereby certain parts of said typewriter may be actuated by said operator, said automatic operator including a continuously driven member, means connected to said finger grip adapted to be operatively

connected to said continuously driven member so as to manipulate said finger grip, a shift rail connected to said means, a star wheel movable to shift said shift rail by engagement therewith, a slide for said star wheel, a pneumatic actuator for moving said slide in one direction, and a spring for returning said slide.

12. The combination with a typewriter, of an automatic operator for said typewriter, said typewriter having a finger grip thereon whereby certain parts of said typewriter may be actuated by said operator, said automatic operator including a continuously driven member, means connected to said finger grip adapted to be operatively connected to said continuously driven member so as to manipulate said finger grip, a shift rail connected to said means, a star wheel movable to shift said shift rail by engagement therewith, master-sheets for controlling the operations of said operator, means for feeding said master-sheets, means for silencing the feed of said master-sheets, a detent for rendering said star wheel capable of shifting said rail, and connections enabling said silencing means to move said detent to an ineffective position.

13. The combination with a typewriter having a finger grip whereby certain of the parts thereof may be actuated, a continuously driven screw, a nut engageable with said screw, a carrier for supporting said nut, means for connecting said finger grip to said carrier, a shift rail connected to said carriage so as to be capable of moving said nut into and out of engagement with said screw, and a star wheel having cammed teeth movable to shift said rail.

14. The combination with a typewriter having a finger grip whereby certain of the parts thereof may be actuated, a continuously driven screw, a nut engageable with said screw, a carrier for supporting said nut, means for connecting said finger grip to said carrier, a shift rail connected to said carriage so as to be capable of moving said nut into and out of engagement with said screw, an actuator, a slide connected to said actuator, a star wheel rotatably mounted on said slide and arranged to engage said rail to shift said nut into engagement with said screw.

15. The combination with a typewriter having a finger grip whereby certain of the parts thereof may be actuated, a continuously driven screw, a nut engageable with said screw, a carrier for supporting said nut, means for connecting said finger grip to said carrier, a shift rail connected to said carriage so as to be capable of moving said nut into and out of engagement with said screw, an actuator, a slide connected to said actuator, a star wheel rotatably mounted

on said slide and arranged to engage said rail to shift said nut into engagement with said screw, and a detent for locking said star wheel against movement in one direction.

16. The combination with a typewriter having a finger grip whereby certain of the parts thereof may be actuated, a continuously driven screw, a nut engageable with said screw, a carrier for supporting said nut, means for connecting said finger grip to said carrier, a shift rail connected to said carriage so as to be capable of moving said nut into and out of engagement with said screw, 10 an actuator, a slide connected to said actuator, a star wheel rotatably mounted on said slide and arranged to engage said rail to shift said nut into engagement with said screw, a detent for locking said star wheel against movement in one direction, and means for moving said detent to an ineffective position.

17. The combination with a typewriter, of a typewriter operator for said typewriter, 25 said typewriter including a platen, and line-space mechanism for said platen, and said typewriter operator including a multiple one-way acting mechanism for causing the actuation of said line-space mechanism by 30 said typewriter operator.

18. The combination with a typewriter, of a typewriter operator for said typewriter, said typewriter including a platen, line-space mechanism for said platen and said typewriter operator including a multiple one-way acting mechanism for causing the actuation of said line-space mechanism by said typewriter operator, and means for rendering said one-way acting mechanism effective or ineffective at will.

19. The combination with a typewriter, of a typewriter operator for said typewriter, said typewriter including a platen, line-space mechanism for said platen and said typewriter operator including a multiple one-way acting mechanism for causing the actuation of said line-space mechanism by said typewriter operator, and means for concomitantly silencing said typewriter operator and rendering said one-way acting mechanism ineffective.

20. The combination with a typewriter, of a typewriter operator for said typewriter, said typewriter including a carriage and 55 said typewriter operator including carriage-returning means, and a camming device having a series of cams operable *seriatim* to operatively connect the carriage with the carriage-returning means and thereby render 60 said carriage-returning means effective to return the carriage.

21. The combination with a typewriter including a traveling carriage, of a typewriter operator for said typewriter including car-

riage-returning means, controlling mechanism for governing the effectiveness of said typewriter operator, and means for passing idly by said carriage-returning means in one direction and positively engaging said carriage-returning means in the opposite direction to enable the return of said carriage, and connections between said controlling mechanism and said last-mentioned means for rendering the latter idle in both directions of movement when said controlling mechanism is effective to silence said operator.

22. The combination with a typewriter including a traveling carriage, a platen mounted on said carriage and line-space mechanism for said platen, of a typewriter operator for said typewriter including camming means for enabling the action of said line-space mechanism and the return of said carriage, and means for silencing said carriage, and means for silencing said camming means at will.

23. The combination with a typewriter having a traveling carriage, of an automatic operator for said typewriter having a carriage-return means for said carriage, and camming means for effecting an operative connection between said carriage-return means and the carriage at any point in the travel of the carriage.

24. The combination with a typewriter having a traveling carriage, of an automatic operator for said typewriter having a carriage-return means for said carriage, camming means for controlling the effectiveness of said carriage-return means, and mechanism for rendering said camming means ineffective to control the effectiveness of said carriage-return means.

25. The combination with typewriting mechanism, of shiftable mechanism operative to perform certain functions of the typewriting mechanism, and an idle wheel for adjusting said shiftable mechanism, a journal for said wheel having a back and forth stroke, said wheel moving rigidly with its journal on one stroke to effect an adjustment of said shiftable mechanism and moving yieldingly on the opposite stroke to idle passing engagement with said shiftable mechanism.

26. The combination with typewriting mechanism, of shiftable mechanism operative to perform certain functions of the typewriting mechanism, an idle wheel for adjusting said shiftable mechanism, a journal for said wheel having a back and forth stroke, and a detent holding said wheel rigid on its journal on one stroke to enable said wheel to adjust said shiftable mechanism and yielding on the opposite stroke to permit an idle movement of said wheel with respect to said shiftable mechanism.

27. The combination with a typewriting

machine having a line-space mechanism, of a shifting star wheel for operating said mechanism and having teeth apiced on one side and cut away for a camming action on the opposite side, a lever forming part of said mechanism operated by the apiced teeth, and a pawl cammed to ineffective position by the camming side.

28. The combination with typewriting mechanism, of shiftable mechanism operative to perform certain functions of the typewriting mechanism, shifting mechanism for adjusting said shiftable mechanism having a back and forth stroke, a detent holding said shifting mechanism rigid on one stroke to enable said shifting mechanism to adjust said shiftable mechanism and yielding on the opposite stroke to permit an idle movement of said shifting mechanism with respect to said shiftable mechanism, and disengaging means for silencing said detent to allow yielding idle movements of said shifting mechanism on normally active strokes of said shifting mechanism.

29. The combination with a typewriting mechanism, including a traveling carriage

and a platen on said carriage, of means for effecting a concomitant traveling movement of said carriage and a line spacing of said platen, shifting mechanism having an effective stroke engaging said means to operate the same and having an idle stroke engaging said means passively, and silencing means for enabling said shifting mechanism to engage said means idly on its normally effective stroke.

30. The combination with a typewriting mechanism, and an operator therefor including a constantly driven member, of shiftable means for making said member effective to accomplish certain functions of said typewriting mechanism, shifting means for said shiftable means yielding solely in one direction when effective and yielding in both directions when ineffective, and connections whereby the starting and silencing of the operator controls said yielding.
